Sigmund Herzog
ATTORNEY

UNITED STATES PATENT OFFICE

NICHOLAS TESTI, OF NEW YORK, N. Y., ASSIGNOR, BY MESNE ASSIGNMENTS, TO GILLETTE SAFETY RAZOR COMPANY, OF BOSTON, MASSACHUSETTS, A CORPORATION OF DELAWARE

SAFETY RAZOR

Application filed January 20, 1930. Serial No. 422,115.

The present invention relates to that class of safety razors in which a flexible blade is clamped between a guard member and a blade backing member, positioning studs being provided to retain the blade and the backing in operative relation to the guard. In this class of razors, commonly referred to as the Gillette type, the dimensions of the stud receiving apertures in the blade transversely of the latter correspond substantially to the diameters of the cylindrical positioning studs, the result being that, when the blade is clamped between the guard and the backing member, the said blade is apt to crack or break in a lengthwise direction while being bent or under tension.

The main object of the present invention is to provide a razor and blade construction, wherein the apertures in the blade are considerably larger than the transverse cross-sections of the studs, whereby not only ready assembling of the elements may be had, but increased flexibility of the blade is obtained for clamping in the blade holder or frame and danger of the blade cracking or breaking in a lengthwise direction while being bent or under tension is overcome; yet perfect alignment of the razor and blade elements is assured.

Another object of the invention is to so design and arrange the stud receiving apertures in the improved blade that the said apertures are adapted to receive the studs of the improved razor construction herein described and also studs of backings of the type of Gillette safety razors on the market.

With these and other objects in view, which will more fully appear as the nature of the invention is better understood, the same consists in the combination, arrangement and construction of parts hereinafter described, pointed out in the appended claims and illustrated in the accompanying drawing, it being understood that many changes may be made in the size and proportion of the several parts and details of construction within the scope of the appended claims without departing from the spirit or sacrificing any of the advantages of the invention.

Two of the many possible embodiments of

the invention are illustrated in the accompanying drawing, in which:

Figure 1 is an end view of a razor constructed in accordance with the present invention; Fig. 2 is a section taken on line 55 2-2 of Fig. 1; Fig. 3 is a top plan view of the construction shown in Figs. 1 and 2, part of the backing member being broken away in order to more clearly disclose the construction; Fig. 4 is a section taken on line 60 4-4 of Fig. 3; Fig. 5 is a plan view of the improved blade used in connection with the construction illustrated in Figs. 1 to 4, inclusive; Fig. 6 is a view similar to the one shown in Fig. 3 showing the improved blade 65 mounted on the ordinary Gillette safety razor; Fig. 7 is a section taken on line 7-7 of Fig. 6; Fig. 8 is a view similar to the one shown in Fig. 3 of a modification of 70 the invention; and Fig. 9 is a plan view of the blade used in connection with the construction shown in Fig. 8.

Referring now first to Figs. 1 to 5, inclusive, of the drawing, the numeral 10 indicates a guard member, provided with suitable guard teeth 11 in its opposite longitudinal edges and having holes 12 adapted to receive cylindrical positioning studs 13, which extend from a backing member 14. The longitudinal axes of these studs are arranged on one side of the longitudinal axis of the backing member, as clearly appears from Figs. 1, 3 and 4 of the drawing, and consequently the centers of the holes 12, the diameters of which exceed somewhat the diameters of the transverse cross-section of the said studs, must be disposed on one side of the longitudinal axis of the guard member 10. Between the studs 13 is disposed on the backing member a screw-threaded pin 15, 80 adapted to pass through a hole 16 in the guard member and to engage with a threaded socket 17 in a handle 18, for the well known purpose. The longitudinal axis of the pin 15 passes through the longitudinal axes of 85 the backing and guard members (see Fig. 3), as usual in the type of Gillette razors on the market.

The studs 13 are adapted to pass through 100 circular apertures 19 in the blade 20, which

is of the thin flexible type having two cutting edges 21. The pin 15, on the other hand, is adapted to pass through a central hole 22 in the blade. The diameter of the last-mentioned hole corresponds substantially to that of the transverse cross-section of the said pin. The diameters of the apertures 19, however, exceed considerably the diameters of the transverse cross-sections of the positioning studs 13 and as herein shown approximate one-third the blade width. The centers of the two apertures 19 and of the hole 22 in the blade are disposed in alignment, more particularly in the longitudinal center line 5 of the blade. Inasmuch as the longitudinal axes of the studs 13 are located on one side of the longitudinal axis of the backing member, it is obvious that the radius of each aperture 19 must exceed in length that of the radius of the transverse cross-section of a positioning stud by the distance between the longitudinal axis of the stud and the longitudinal center line of the backing member, in order to obtain contact between the 10 stud and the edge of the aperture through which the stud passes (Fig. 3). From the last-mentioned figure it appears that each stud contacts with the edge of its respective aperture in the blade at a single point only, and that the bounding figure of the transverse cross-section of a stud and the circular edge of the aperture, through which it passes, are eccentrically located, contacting outside 15 of the longitudinal axis of the razor frame. 20 25 30 35 40 45 50 55 60 65 68 69 70 75 80 85 90 95 100 105 110 115 120 125 130

One of the advantages of the improved construction is that, when the blade is clamped in the blade holder, danger of the blade cracking or breaking in a lengthwise direction while being bent or under tension is overcome. This is mainly due to the fact that each positioning lug contacts with the edge of the respective blade aperture at a single point only, and that the said aperture is considerably larger than the transverse cross-section of the stud. Due to the last mentioned arrangement, the flexibility of the blade is materially increased.

Referring now to Figs. 6 and 7 of the drawing, the numeral 23 indicates a guard member of the ordinary Gillette construction and the numeral 24 the blade backing member thereof. In this construction the positioning studs 25 are disposed in the longitudinal axis of the backing member, and the distance between the longitudinal axis of each stud 25 and the threaded pin 15' is shorter than the distance of the corresponding elements of the construction shown in Figs. 1 to 4, inclusive, by the difference between the radii of the blade apertures 19 and the transverse cross-sections of the positioning studs, the studs shown in Figs. 1 to 4, inclusive, being of the same dimensions as the studs shown in Figs. 6 and 7 of the drawing. Consequently, when the improved blade 20

is mounted on the razor frame shown in Figs. 6 and 7 of the drawing, the studs 25 contact with the edges of the blade apertures 19 in the longitudinal axis of the said blade. The construction, therefore, has the advantages described in connection with Figs. 1 to 5, inclusive, of the drawing, and the blade has the added advantage that it may be used in connection with the improved razor construction shown in Figs. 1 to 4, inclusive, of the drawing and also in connection with the ordinary Gillette razor illustrated in Figs. 6 and 7 of the drawing. 70 75

The modification illustrated in Figs. 8 and 9 of the drawing differs from those above described only in that the positioning stud receiving apertures 26 in the modified blade 27 are square in shape, the length of each side of the square corresponding to the diameter of an aperture 19 in the blade construction shown in Fig. 5. Therefore, this blade may be used in connection with the razors shown in Figs. 1 to 4, inclusive, and also with the razors shown in Figs. 6 and 7 of the drawing, the latter arrangement being illustrated in Fig. 8. 80 85 90 95

It will be noted that the blade apertures described herein are of regular contour, one being circular and the other square. It is obvious that instead of the square configuration any other regular polygonal design may be used without departing from the invention. 100

What I claim is:

1. A safety razor including a blade holder, two spaced cylindrical positioning studs on said holder having their longitudinal axes located on one side of the longitudinal axis of said holder, a clamping pin on said holder disposed centrally in the longitudinal axis thereof, and a blade having spaced positioning stud-receiving apertures and a clamping-pin receiving opening, each of said positioning stud receiving apertures being of regular contour and having its center disposed in the longitudinal axis of said blade, each aperture being both transversely and longitudinally of the blade larger than the diameter of the respective positioning stud. 105 110

2. A safety razor including a blade holder, two spaced cylindrical positioning studs on said holder having their longitudinal axes located on one side of the longitudinal axis of said holder, a clamping pin on said holder disposed centrally in the longitudinal axis thereof, and a blade having spaced circular positioning stud receiving apertures and a clamping pin receiving opening, the centers of said apertures being disposed in the longitudinal axis of said blade and each aperture having a diameter of a size that the respective stud contacts with the edge thereof. 120 125

3. A safety razor blade having a clamping pin receiving hole and a positioning stud receiving aperture on each side thereof, said 130

apertures being of regular outline and their centers being disposed in the longitudinal center line of said blade in alignment with the center of said hole, each aperture being larger
5 than said hole so that its edge is adapted to contact at one point only with a positioning
stud passing eccentrically through said aper-
ture with its longitudinal axis located either
in the longitudinal center of said blade or
10 outside of the same.

4. In a safety razor blade according to
claim 3, said hole and said apertures being
each of circular configuration, and said aper-
tures having a diameter not less than one-
15 third of the blade width.

Signed at New York city, in the county of
New York and State of New York, this 8th
day of January, A. D. 1930.

NICHOLAS TESTI.
